CLAIM

The ornamental design for a safety blood collection needle device, as shown and described.

DESCRIPTION

FIG. 1 is a perspective view of a safety blood collection needle device having a patient needle guard disposed over a needle, a non-patient needle guard, and a shield in a first initial position in accordance with an embodiment of the present invention;

FIG. 2 is a top view of the safety blood collection needle device of FIG. 1;

FIG. 3 is a left side view of the safety blood collection needle device of FIG. 1;

FIG. 4 is a front view of the safety blood collection needle device of FIG. 1;

FIG. 5 is a rear view of the safety blood collection needle device of FIG. 1;

FIG. 6 is a right side view of the safety blood collection needle device of FIG. 1;

FIG. 7 is a bottom view of the safety blood collection needle device of FIG. 1;

FIG. 8 is a perspective view of the safety blood collection needle device of FIG. 1 having the patient needle guard removed and the shield in a retracted second alternate position in accordance with an embodiment of the present invention;

FIG. 9 is a top view of the safety blood collection needle device of FIG. 8;

FIG. 10 is a left side view of the safety blood collection needle device of FIG. 8;

FIG. 11 is a front view of the safety blood collection needle device of FIG. 8;

FIG. 12 is a rear view of the safety blood collection needle device of FIG. 8;

FIG. 13 is a right side view of the safety blood collection needle device of FIG. 8;

FIG. 14 is a bottom view of the safety blood collection needle device of FIG. 8;

FIG. 15 is a perspective view of the safety blood collection needle device of FIG. 1 having the patient needle guard removed and the shield in a shielded third alternate position in accordance with an embodiment of the present invention;

FIG. 16 is a top view of the safety blood collection needle device of FIG. 15;

FIG. 17 is a left side view of the safety blood collection needle device of FIG. 15;

FIG. 18 is a front view of the safety blood collection needle device of FIG. 15;

FIG. 19 is a rear view of the safety blood collection needle device of FIG. 15;

FIG. 20 is a right side view of the safety blood collection needle device of FIG. 15; and,

FIG. 21 is a bottom view of the safety blood collection needle device of FIG. 15.

In the Figures, the features shown in broken line are for the purpose of illustrating surface features and form no part of the claimed design.

The broken lines depict portions of the needle device that form no part of the claimed design.
